CLAIM

The ornamental design for a slide clamp, as shown and
described.

DESCRIPTION

FIG. 1 is a front, top, and right-side perspective view of the
slide clamp, which may be used to occlude a fluid line within
the slot, showing our new design;

FIG. 2 is a front elevation view thereof;

FIG. 3 is a back elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a front, top, and right-side perspective view of
another embodiment of a slide clamp, showing our new
design;

FIG. 9 is a front elevation view thereof;

FIG. 10 is a back elevational view thereof;

FIG. 11 is a right-side elevational view thereof;

FIG. 12 is a left-side elevational view thereof;

FIG. 13 is a top plan view thereof; and,

FIG. 14 is a bottom plan view thereof.

The ornamental design which is claimed is shown in solid
lines in the drawings. The broken lines show portions of the
slide clamp that form no part of the claimed design.
